UNITED STATES PATENT OFFICE.

JOHN BROOKS, OF DETROIT, MICHIGAN.

PILL-MACHINE.

SPECIFICATION forming part of Letters Patent No. 290,524, dated December 18, 1883.

Application filed April 14, 1883. (No model.)

To all whom it may concern:

Be it known that I, JOHN BROOKS, of Detroit, county of Wayne, State of Michigan, have invented a new and useful Improvement 5 in Pill-Machines; and I declare the following to be a full, clear, and exact description of the same, such as will enable others skilled in the art to which it pertains to make and use it, reference being had to the accompanying drawings, which form a part of this specification.

My invention consists in the combination of devices and appliances hereinafter specified, and more particularly pointed out in the claims.

15 In the drawings, Figure 1 is a side elevation of a device embodying my invention. Fig. 2 is a front elevation. Fig. 3 is a side elevation of my compressing mechanism. Fig. 4 is an end elevation, and Fig. 5 is a plan view of the 20 same. Fig. 6 is a side elevation of the feeding mechanism. Fig. 7 is an end elevation of the same. Fig. 8 is a plan view thereof. Fig. 9 is a variation of the compressing mechanism in side elevation. Fig. 10 is a plan view of the 25 same. Fig. 11 is a plan view of the upper and lower pair of rollers.

The object of my invention is to provide an improved pill-making machine, simple in its construction, adapted to be run by power, and 30 to dispense with the necessity of hand-work.

In the manufacture of said articles heretofore, difficulty has been experienced in the power-machines which have been devised for the manufacture of pills. They have proved 35 unsatisfactory, from the fact the pills made have been very uneven and have differed greatly in weight. This has necessitated the use of hand-labor largely. It is the purpose of my invention to overcome these difficulties, and to 40 provide a power-machine by which pills of uniform size and weight may be manufactured.

In carrying out my invention, as illustrated in the drawings, A represents the frame. B is the drive-wheel. b is its shaft; b', a suitable driving-pulley, mounted upon said shaft.

45 C and C' represent a set of rollers provided with a suitable number of grooves, e, adapted to receive a portion of the mass to be shaped into the pills. C' and C'' are the shafts of said rollers. The roller C is provided with an annular series of cogs, c', adapted to mesh with similar cogs on the drive-wheel B. c'' is an 50 annular series of cogs upon the roller C', also

adapted to mesh with similar cogs upon the drive-wheel B. It is evident that the construction is such that the rollers C and C' will be driven in opposite directions, as indicated by the arrows.

I design to construct the annular series of cogs c' and c'' upon their respective rollers of 55 different diameters, so that difference in the speed of the two rollers shall be secured, the roller C' being driven with greater velocity.

D and D' represent another set of rollers, similar in construction to the rollers C and C', 60 each provided with a series of grooves, d, and are also driven by an annular series of cogs, d' and d'', adapted to mesh with the drive-wheel B, said annular series of cogs being of different diameters to give said rollers a difference of 70 speed. d' and d'' are the shafts of said rollers.

E is the feeding-receptacle in which the mass is placed. E' is a follower adapted to be reciprocated in said receptacle by means of a screw, E'', said screw operated by the ratchet-wheel F, the 75 hub of which, f, is screw-tapped to work upon the screw E''. The ratchet-wheel is provided on its periphery with a suitable series of ratchet-teeth, f''. The wheel is driven by means of a series of pawls, f'', secured upon an arm, F', 80 loosely engaged upon the hub of the ratchet-wheel at one end, and at the other having a loose engagement with the connecting-lever F'', said lever eccentrically connected with a slotted disk, F'', the slot f''' allowing the engagement of the lever F'' with the disk at any 85 desired point, to secure the desired throw of said lever. The disk F'' is driven by means of an additional gear, F'' and F'', the gear F'' driven by means of a gear-wheel, F'', located 90 upon the shaft f'', the gear-wheel F'' meshing with the cogs d' upon the roller D. It is evident that as the disk F'' is rotated a reciprocating motion will be given to the arm F', and the pawl f'' will be caused to drive the ratchet-wheel F, by means of which the follower E' will be driven into the receptacle E, forcing 95 the mass before it.

e represents a series of holes of suitable size in the end of the receptacle, through which the 100 mass will be forced by the follower. I prefer that said orifices shall be constructed in a removable plate, E'', said plate being dovetailed or otherwise suitably secured in the end of the receptacle. In this manner I am enabled to 105 use a series of plates E'', provided with orifices

e of various diameters, to suit the size of pills desired to be manufactured.

In order that the mass may be forced more freely through the holes *e*, I prefer to taper the adjacent end of the receptacle, as shown in dotted lines in Fig. 1.

G is a suitable knife by which the material forced through the holes *e* is cut in the desired lengths. This knife is operated by means of 10 an arm, *G'*, suitably connected with the lever *G*, said lever provided with a friction-roller, *g*. The lever *G* is operated by means of a cam, *g'*, upon the shaft *b* of the drive-wheel *B*. The arm *G'* has its fulcrum at *g* upon the supporting-arm *G*. It is evident that by this mechanism a suitable reciprocating motion will be given to the knife *G*, by means of which the mass will be cut as desired, as it issues from the holes *e*. The receptacle *E*, I prefer to make 20 removable.

E' is a suitable saddle in which the ratchet-wheel *F* is located, and supports the screw *E*, the saddle serving to prevent an end motion of the ratchet-wheel. The screw *E* and the 25 saddle are provided with a key-seat, said key-seat provided with a key or feather to prevent the turning of the screw *E* when it is forced forward by means of the ratchet-wheel. The follower *E'* may be retracted by suitable 30 means—as for instance, the end of the screw *E* may be squared to receive a wrench or crank.

g is a suitable bridge or support for the front of the receptacle. As the mass is cut away the 35 severed portions fall into a suitable funnel, *H*, from whence they are delivered into the grooves *c* of the rollers *C* and *C'*. The roller *C* tends to carry the severed portions of the mass downward, while the roller *C'* tends to carry them upward, thus holding the mass for a suitable season in engagement with said rollers, the more rapid speed of the roller *C'* eventually carrying the revolving portions downward into the funnel *H'*. When delivered from the rollers 40 *C* and *C'*, the pills will be partially shaped, and are again delivered from the funnel *H'* to the grooves *d* in the lower pair of rollers *D* and *D'*, which rotate in opposite directions, as already described, which opposite motion serves 45 to hold the pills for a suitable season in engagement with said rollers, thus completing the rounding process, and they are ultimately delivered into a suitable receptacle beneath. I desire to locate the funnels *H* and *H'* in such 50 a manner that should the upward motion of the rollers *C* and *D* chance to carry the pills upward out of engagement with the rollers *C'* or *D'*, this action will be prevented by their engagement with the adjacent portion of said funnels. It will be understood that the mass 55 of which the pills are made will have some tendency to stick to the rollers, the consequence of which, so far as the rollers *C* and *D* are concerned, will be obviated by the adjacent portions of the funnels *H* and *H'*, as already described.

In order to prevent the pills being carried

under the rollers *C* and *D'*, any suitable means may be provided—as, for instance, wires may be stretched across and beneath said rollers at 70 suitable points, as indicated at *c* and *d*—by means of which any pills that may cling to said rollers shall be disengaged therefrom; also, any tendency of the severed portions of the mass clinging to the knife may be obviated by any suitable means, such as a wire located as shown at *g*.

It is obvious that it will be essential that the grooves *c* upon the upper pair of rollers should be located opposite each other. The 80 same is true of the grooves *d* on the lower pair of rollers. In order to secure this adjustment, the shafts of said rollers run upon central bearings, *I*, which are screw-threaded, through the adjacent portions of the frame, by means of 85 which the location of said rollers may be adjusted as desired. The rollers *C* and *D* have their bearings in the adjacent portions of the frame; but in order to secure the proper adjustment of the rollers *C* and *D'* to the rollers 90 *C* and *D*, I provide a saddle-piece or bracket, *J*, constructed with slots *j*, in which the rollers *C* and *D'* have their bearings, said bracket having an adjustable connection with the frame by means of bolts *j'*, passing through the 95 slot *j*.

I have described the severed portions of the mass as falling directly from the holes *e* into the funnel *H*, and I contemplate such an operation of the device as coming within the 100 scope of my invention. I contemplate, however, providing suitable compressing mechanism adapted to receive the severed portions of the mass before they fall into the funnel *H*. This compressing mechanism is shown particularly in Figs. 3, 4, and 5, in which *K* is a suitable cam located upon the shaft *C*, although it might be, if desired, located upon the shaft *d*.

K and *K'* represent a pair of cam-levers located upon opposite sides of the cam-shaft 110 *C*, said levers connected at their lower ends by a suitable spring, *K*. The levers *K* and *K'* are provided at their upper extremities with the compressing-arms *k* and *k'*, each of 115 said arms adapted to drive a series of compressors, *k* and *k'*, said compressors having a pivoted connection with said compressing-arms, as shown at *k* and *k'*. The compressors are constructed with a suitable concavity at 120 their inner ends, and slide upon suitable pins, *L*, secured in a standard, *L'*. It is evident that as the cam *K* revolves a reciprocating motion will be given to the compressing-arms *k* and *k'*, and also to the compressors *k* and *k'* upon 125 the pins *L*. Their concavities are located so as to close immediately below the holes *e* in the end of the receptacle *E*. The compressors are made to open and close at the desired intervals by a suitable adjustment of the cam *K* upon the shaft *C*. These compressors reciprocate in a straight line.

Immediately below the compressors I locate reciprocating plates *M*, provided with corrugations, said plates being caused to recipro-

cate by a pair of cam-levers similar to K' and K², located upon the opposite side of the machine, and caused to operate by a cam similar to K upon the opposite end of the shaft C², 5 said plates connected with said cam-levers by means of connecting-arms similar to k and k', the location of the two cams upon the opposite ends of the shaft C² being such that said plates and said compressors shall be reciprocated alternately. When the knife G descends, said plates are closed and catch the severed portions of the mass, which portions are held by said plates until the compressors k² and k³ close thereon, engaging said severed portions between the concavities. By this 15 operation the severed portions will be considerably rounded before they descend into the funnel H, when said compressors are opened. Upon the opening of said passages, however, 20 should the pill material cling to the compressors it will be seen that when they are forced back upon the pins L any clinging substance will be forced off from contact with the compressors.

25 I would have it understood that I design to use this compressing mechanism or not, as may seem desirable. I would also have it understood that instead of two sets of compressors, k² and k³, provided with their separate operative mechanisms, I may use one of said compressors and its operative mechanism, said compressors being located directly in front of the holes e, the construction being such that the concaved faces of the compressors will 30 close against the knife as it descends. By constructing the compressors in this manner, the amount of the mass forced through the holes e to be severed may be more effectually controlled, and the pills be made of more uniform 35 weight.

40 Figs. 9 and 10 show a variation of the compressing mechanism, in which the knife G is provided with wedge-shaped bearing-surfaces g⁵. A single set of compressors, k³, mounted 45 upon pins L, are provided with springs N, adapted to force said compressors forward, the concaved end of said compressors being opposite to the orifices e in the receptacle, the construction being such that when the knives 50 are forced downward the wedge-shaped faces will force the compressors back the desired distance, and when the knife is lifted the springs will force the compressors forward upon the mass.

55 I would have it understood that I desire to employ any of these means herein described for compressing the severed portions of the mass, or they may be entirely dispensed with, if preferred.

60 The springs N may be retracted by means of an arm, N', provided with an anti-friction roller, n, adapted to engage against the wedges g⁵ upon the knife.

65 It is desirable in a pill-machine to provide mechanism whereby the pills may be made spherical or oval, as may be desired. It is evident that the grooves e and d may be of

any suitable form. Should it be preferred to manufacture spherical pills, I would construct said grooves in the upper and lower pair of 70 rollers to correspond. Should it be desired, however, to construct the pills oval in shape, I would construct the upper pair of rollers each having a series of semicircular grooves, as shown at e, Fig. 11; but the lower pair of 75 rollers I should prefer to construct with grooves semi-oval in form, as shown at d, Fig. 11. By this construction it is evident that the pill, after being rolled into contact with the upper series of rollers, will fall to the lower 80 series and be engaged in the semi-oval grooves, and be formed into an oval shape, as shown at D². I would have it understood, however, that I design to construct said grooves upon both pairs of rollers of any desired shape. 85

What I claim is—

1. In a pill-machine, the combination, with a suitable frame, of two pairs of grooved rollers arranged to rotate in the same vertical plane, and one pair located under the other 90 pair, the construction being such that the mass will be delivered from one set of rollers to the other, driving mechanism adapted to drive said rollers, and in connection therewith suitable feeding mechanism, substantially 95 as described.

2. In a pill-machine, the combination, with a suitable frame, of two pairs of grooved rollers arranged to rotate in the same vertical plane, and one pair located directly above 100 the other, the construction being such that the mass will be delivered from the upper downward directly to the lower pair, and a driving-shaft geared with both pairs of rollers in such a manner that the rollers of each pair shall have a 105 difference of speed, whereby the severed portions of the mass shall be held suitably in suspension in engagement with said rollers, substantially as and for the purpose described.

3. In a pill-machine, the combination, with 110 a suitable frame, of two pairs of grooved rollers arranged to rotate in the same vertical plane, and one pair located directly above the other, the construction being such that the mass will be delivered from the upper to the 115 lower pair, and a driving-shaft geared with both pairs of rollers in such a manner that the rollers of each pair shall have a difference of speed, said rollers provided with means whereby they may be suitably adjusted in any 120 desired direction, substantially as and for the purpose described.

4. In a pill-machine, two pairs of grooved rollers arranged to rotate in the same vertical plane, and one pair located directly above the 125 other, said rollers provided at each of their sides with an adjustable center bearing, said bearings having an adjustable connection with their supports, whereby said rollers may be adjusted, substantially as described.

5. In a pill-machine, the combination, with a suitable frame, of two pairs of grooved rollers arranged to rotate in the same vertical plane, and one pair located directly above the 130

other, and in connection therewith vertical brackets J, said brackets having an adjustable connection with the frame, and provided with adjustable center bearings for the rollers, substantially as and for the purpose described.

6. In a pill-machine, the combination, with a feeding-receptacle, of a removable disk provided with discharge-orifices e, and in connection therewith a follower adapted to be reciprocated in said receptacle by suitable mechanism, substantially as described.

7. In a pill-machine, a feeding-receptacle provided with discharge-orifices e, a follower provided with a screw-cut stem, and in combination therewith a ratchet-wheel upon said stem, said ratchet-wheel adapted to be driven by one or more pawls operated by suitable reciprocating mechanism, substantially as described.

8. In a pill-machine, a feeding-receptacle provided with discharge-orifices e, a follower provided with a screw-cut shaft, and in combination therewith a ratchet-wheel upon said shaft, said ratchet-wheel adapted to be driven by one or more pawls located upon a reciprocating arm, said arm connected with the driving-gear of the machine by suitable intervening mechanism, substantially as described.

9. The combination, with a suitable frame, of two pairs of grooved rollers, one pair located above the other, the construction being such that the mass will be delivered from one set of rollers to the other, and in connection therewith suitable feeding mechanism, and funnels H and H', adapted to receive the severed mass from the feeding mechanism and direct it into the grooves of said rollers, substantially as described.

10. The combination, with a suitable frame, of two pairs of grooved rollers, the construction being such that the mass will be delivered from one set of rollers to the other, funnels H and H', adapted to direct the severed mass into the grooves of said rollers, said funnels adapted to prevent the mass from being carried upward, and in connection therewith means by which the mass shall also be prevented from being carried under the rollers, substantially as described.

11. In a pill-machine, the combination, with the feeding-receptacle provided with orifices e, of a knife, G, said knife adapted to be reciprocated by suitable mechanism in such a manner as to sever the mass forced through said orifices, substantially as described.

12. The combination, with the feeding-receptacle provided with orifices e, of a knife, G, said knife secured to a reciprocating arm, and mechanism for reciprocating said arm, the construction being such that the mass will

be severed by said knife as it is forced through said orifices, substantially as and for the purpose described.

13. In a pill-machine, the combination, with two pairs of grooved rollers so arranged and constructed that the mass will be delivered from one set of rollers to the other, of a driving-shaft geared therewith, mechanism adapted to feed the mass in severed portions to said rollers, and in addition thereto suitable compressing mechanism adapted to compress said severed portions of the mass and deliver them to the rollers, substantially as described.

14. In a pill-machine, compressing mechanism consisting of a pair of cam-levers on opposite sides of a cam-shaft, said levers connected at their lower ends by a suitable spring and at their upper extremities provided with compressing-arms h and h', and in connection therewith a series of compressors, h² and h³, said compressors mounted upon a series of pins, L, the construction being such that the compressors may be reciprocated upon said pins, substantially as and for the purpose described.

15. In a pill-machine, compressing mechanism consisting of two pairs of cam-levers on opposite sides of a cam-shaft and adapted to be operated by said cam-shaft, a spring adapted to retract said levers, compressing-arms h and h', secured thereto, a series of compressors connected with said arms, pins L, upon which the compressors are mounted, and in addition thereto corrugated plates similarly operated by the opposite levers, the construction being such that the compressors may be reciprocated upon said pins, substantially as and for the purpose described.

16. In a pill-machine, the combination, with the feeding-receptacle provided with orifices e, of a knife, G, adapted to be reciprocated by suitable mechanism, and provided with wedge-shaped faces, a series of compressors mounted upon a series of pins, and in connection therewith suitable springs adapted to force the compressors forward against the mass forced through the orifices e, substantially as described.

17. In a pill-machine, a series of compressors mounted upon pins, and in connection therewith, means by which said compressors may be reciprocated upon the pins, substantially as and for the purpose described.

In testimony whereof I sign this specification in the presence of two witnesses:

JOHN BROOKS.

Witnesses:

N. S. WRIGHT,
WILLIAM FORD.
